H. M. FRIENDLY

CALL REGISTER FOR TELEPHONE SYSTEMS

Original Filed Oct. 27, 1920

UNITED STATES PATENT OFFICE.

HERBERT M. FRIENDLY, OF CHICAGO, ILLINOIS.

CALL REGISTER FOR TELEPHONE SYSTEMS.

Application filed October 27, 1920, Serial No. 420,018. Renewed June 25, 1926.

The present invention has for its broad objects the metering or integrating of telephonic calls completed through telephone exchange systems.

5 The invention in the specific form chosen for the illustration herein contemplates a so-called two-wire common battery automatic telephone system as has been widely used, the present invention necessitating novel departures from equipments heretofore known, so far as I am aware, in attaining the new objects, while retaining certain operative functions which are known.

10 The present invention contemplates the following and other novel objects:

(a) Means for metering or integrating the chargeable calls completed from a subscriber's line, taking into account a different charge value depending upon the hour at 20 which the call is made.

(b) Means for metering or integrating a different value chargeable on calls to trunks than for normal calls or simply local calls. That is to say, the present invention also contemplates variable charges depending upon the destination of the call; whether the call is local within the office district, trunked to certain local numbers within the office district or trunked to a remote office district.

25 (c) Means for metering or integrating the total number of completed chargeable calls regardless of the charge value of such calls.

The foregoing, and other novel objects of the present invention, and the invention itself 35 will be understood from the following description thereof, together with the accompanying drawings designated Figs. 1 and 2.

Fig. 1 is a schematic layout of a system embodying the invention.

40 Fig. 2 is a schematic representation of the charge-varying element controlled by a commonly used control time clock through the agency of its closing an electrical circuit at certain periods.

45 Like parts are similarly designated in the figures.

In automatic or machine switching telephone systems the cost of establishing a connection to the operating company depends almost wholly upon a readiness-to-serve expense or cost, rather than largely to a direct cost of manually establishing the connections by the efforts of human agencies at the central offices. That is to say, the costs for ren-

dering switching service (considered aside from the cost of providing telephonic connections with subscribers' premises simply) is dependent upon the amount of operating equipment and correlated plant construction necessary to serve the switching needs of the exchange. The amount of equipment and plant construction required for such switching will depend not so much on the total number of calls completed in a day period, or their duration, for example, as upon the number of calls which may be established or in duration at any particular instant. Obviously, enough switching equipment and correlated plant construction must be provided to serve any traffic exigency. Thus, said amount of equipment is irrespective of how long it may be required.

Records of traffic show there are pronounced periods of heavy traffic demands upon the system. These vary in business districts from residence districts. For example, in certain hours of the night there is small demand for switching in all districts. At certain evening hours there is a relatively large switching demand in residence districts and a corresponding low demand in business districts. Again, at certain day periods the switching demands in the business districts are very great, while not so relatively pronounced in residence districts.

However, as adverted to, central office and plant construction must contemplate instantaneous traffic, rather than total traffic, regardless of how brief the duration of the maximum demand period. So the charges incident to the investment in the equipment and plant employed in switching has become a fixed charge upon all the users and subscribers regardless of how sparingly the service is used by certain ones of them at periods of general small service demand.

A salient object of the present invention is to afford a means of adjusting the proper charge (based upon cost of supplying the service) to each subscriber depending upon his demands which influence greater investment for switching equipments and correlated plant.

The general principle of the charge, contemplated in the present invention obtained by a variable-charge integrating meter or impulse register, is to assume (as exemplified herein) four points or places as an equitable relative charge for each completed call at the

period of greatest general demand; then vary this down to one point at off-demand periods. Thus, in the exampled instance, a call made between ten a. m. and twelve m. and between 5 two p. m. and five p. m. would register as four points; a call between eight a. m. and ten a. m., and between five p. m. and eight p. m., would register three points; and a call between ten p. m. and six a. m. would register one point. 10 The foregoing in this paragraph assumes the call to be one within the same office district, or otherwise a "local" call.

If, however, the call is to a remote (or to a special point) office of the exchange, an additional point will be registered, and if the call is to a still more remote office, two additional points will register. Moreover, if the call is to the latter remote office, between eight p. m. and ten p. m., between six a. m. and eight 20 a. m., but one point will be registered and if the call is to the former remote office or the latter remote office, between ten p. m. and six a. m., no points will be added on account of the call being other than a "local" one.

25 The term "local" may be understood as to a general subscriber of the same exchange district or office as the calling subscriber. However, it would not include specific groups of subscribers in the same office. For example, groups from which lines extend to some 30 particular group or sub-exchange, and upon which a special charge is to be collected.

Thus, employing the present invention, an 35 incentive will be inspired in subscribers to avoid calling over the telephone at periods of generally heavy traffic and thereby reduce the quantity of equipments and plant which would otherwise be necessary for a given unrestrained total traffic. It will therefore permit 40 much traffic which the high rates which contemplate unrestrained use discourage, and the operating company can therefore consistently formulate rates enabling the public to enjoy a greater use of the telephone service 45 for a given total sum, by suitably timing its calls. Reference is made to my co-pending application for U. S. patent Serial No. 522,842, filed December 16, 1921.

Referring to Fig. 1, the calling telephone 50 set P is of the usual series type having a sending device 20 of the general class as shown in British patent to Dicker, No. 29,654 of 1910.

The telephone P is connected over conductors 21 and 22 to armature 23 and 24 respectively of a pre-selector of my invention. A said pre-selector is individual to each calling line and has access to a plurality of first selectors, only one of which is shown. The said first selectors each have access to a plurality of connectors, only one of which is shown. Of course, second, and even subsequent selectors can be introduced between the first selector and the connector, but the adaptation of the present invention does not 65 require them for its successful operation.

The pre-selector is of the general class as shown in U. S. patent to Lamb No. 1,193,160 granted August 1, 1916. However, it is modified to embody the present invention.

The first selector (designated F. S.) is of the general class as shown in U. S. patent to Keith and Erickson No. 815,321, granted Mar. 13, 1906, of course, modified in mechanical and circuit details to operate on the so called two-wire principle, and to embody the present 75 invention.

The connector is of the general class as shown in U. S. patent to Keith and Erickson No. 815,176, granted March 13, 1906, of course, modified in mechanical and circuit details to 80 operate on the so called two-wire principle.

The telephone set Q is similar to P and is shown as a called telephone on bank contact set "eleven" and is reached over line conductors 25 and 26.

In practice it is usual to employ a single battery source and this battery has one of its poles permanently grounded. Also, it is usual to employ a single ground, the said battery and ground being multiplied to terminals of the elements adapted to each respectively. To simplify the drawings and description, the battery and ground is shown as independent sources throughout, wherever applied. In the descriptions, when a circuit is traced to a winding, the opposite terminal of which is shown applied to grounded battery or to ground, the described circuit is to be considered as traced to ground through the winding and battery, or direct to ground as indicated.

95 Referring to Fig. 2. The three cams 27, 28 and 29 are mounted rigidly on a shaft 30 which is adapted to revolve, driven by the drive magnet (designated Drive M.). The shaft is assumed to revolve one time in each twenty-four hours, thus turning fifteen degrees of its circumference each hour. The drive magnet is controlled by an ordinary time clock adapted to close an electrical circuit from a cam 31 engaging grounded spring 32, which latter in turn engages and grounds spring 33. The spring 32 applies its ground to spring 33 at every fifteen-minute period. Time clocks adapted to close electrical circuits at stated periods are not new, used for master control of secondary clocks. Such a master time clock is adapted for use in the present invention, of course, adjusted to close its control contacts at each fifteen-minute 100 period, as contemplated in the present invention. Thus, the drive magnet actuates one time at the end of every fifteen-minute period. The toothed wheel 34 has ninety-six teeth, so it revolves one time in each twenty-four hour period, driven through the agency of the drive magnet armature A.

105 Cam 27 is adapted to flex spring 35 against grounded spring 36 from six a. m. until ten p. m. and to allow it to remain disengaged 110

5 during the rest of the twenty-four hour period. Cam 28 is adapted to flex spring 37 against grounded spring 38 from eight a. m. until eight p. m. and to allow it to remain dis-
 10 engaged during the rest of the twenty-four hour period. Cam 29 is adapted to flex spring 39 against grounded spring 40 from ten a. m. until twelve m. and from two p. m. until five p. m. and to allow it to remain dis-
 15 engaged during the rest of the twenty-four hour period.

10 The cams have been referred to as mounted rigidly to the shaft 30, in fact these cams are mounted rigidly, but interchangeably so
 15 the control of the springs 35—36, 37—38 and 39—40 may be varied. For example, it might be desirable to change the meter charge as controlled by the cams on Saturdays, Sundays or holidays. This may be readily done
 20 by changing the cams to operate the spring sets 35—36, 37—38, and 39—40 suitably. For example, a cam may be substituted for cam 29 on Saturdays with the operative portion between "2P" and "5P" omitted. Further,
 25 cams 28 and 29 may be removed and not substituted for on Sundays and holidays, etc.

It is to be borne in mind a single set of cams and springs, cooperative with the circuit-closing device 31, will suffice for an exchange 30 office of moderate size, since it is companion to the interrupter (designated Intr.) and that the interrupter may be common to all meters and pre-selectors of the exchange office. The conductors leading from the interrupter 35 which are common to all pre-selectors and meters are drawn heavy.

40 The interrupter device is adapted to cyclically function automatically approximately each ten seconds. However, this period may be varied. The function of the interrupter device is to independently short circuit the respective pairs of contacts successively and also to independently apply ground from bus-bar 41, to contact 42 just before the lower pair of contacts 44—45 are engaged and to apply the said ground on bus-bar 41 to contact 43 just after disengaging the upper set of contacts 46—47 incident to each upward stroke.

45 The insulating member 48 joins pivoted and grounded member 49 and the pivoted member 50. The pivot of member 49 has a degree of friction so when member 51 is attracted under the influence of the solenoid 52, and member 51 encounters member 50, member 49 will disengage from spring 53, de-energizing the solenoid 52 and allowing the plunger carrying member 51 to recede slowly under dash-pot restraint until member 49 is reengaged with spring 53. The said friction causes the member 49 to remain where moved until reengaged by the member 51, whereupon contact 53 is caused to reengage member 49 and re-energize the solenoid 52, causing the member 51 to be raised as before.

This cycle of operations continues automatically, as set forth, approximately each ten seconds. It will be noted here that bus-bar 41 is grounded only while member 49 engages contact 53.

70 While I have shown an interrupter of the solenoid type, it is clear a rotary interrupter driven by a motor will suffice; it being only required that the circuit relations with respect to the contacts be periodically changed 75 as set forth.

80 In elucidation of the present invention the performance of the equipments will be detailed under different assumed operative conditions.

Assuming a call from telephone P to telephone Q (the listed number of which is "111"), springs 35—37 and 39 being free from their respective companion grounded springs and the cams 27, 28 and 29 in the position 85 shown; upon the receiver of telephone P being removed from hookswitch to initiate the call (assuming the pre-selector to have been resting on contacts leading to an idle selector) a circuit may be traced from grounded resting contact 60 of relay A, armature 24, conductor 22, telephone P, conductor 21, armature 23, resting contact 61 to winding of slow-releasing relay B, causing said B to actuate. A circuit can now be traced from 90 winding of motor magnet (designated Motor M.) armature 62 thereof, resting contact 63, conductor 64, winding of relay A, conductor 65, working contact 66 to grounded armature 67. The motor magnet remains inert 100 as it is adjusted to not operate through the obstruction offered by the winding of relay A. However, relay A will operate under the condition. This will cause armature 23 to engage working contact 68, and armature 24 to engaging working contact 69. This extends the conductors 21 and 22 direct to conductors 70 and 71 and to the line wipers 72 and 73 respectively. The latter, as assumed, engage bank contacts 74 and 75 respectively, 110 leading to the first selector. Conductor 70 includes the outside winding of shunted relay C, the object of which will appear presently. This first selector may be of the specific type designated "D" shown in the cited patent to Lamb. Assuming this, when a closed circuit condition ensues including the pre-selector leading-in conductors 21 and 22, the release trunk 76 of the first selector leading to a contact 77 on the pre-selector companion to the line contacts 74 and 75 will become grounded. Thus, private wiper 78 to which attaches conductor 79 will become grounded following the actuation of relay 120 A. Armature 80, which is now grounded and which engages working contact 81, leading to conductor 65 applies a supplemental ground to said 65 thus insuring the ground at the lower winding terminal of relay A 125 after the period of disassociated relay B ex-

- pires, for relay B becomes deenergized incident to the actuation of relay A.
- Incident to the actuation of relay A grounded armature 82 engages its working contact 83. This applies ground over conductor 84 through resistance 85, conductor 86 to inside winding of relay C, energizing said winding. However, the energization is not sufficient to cause actuation of said C unless the current in the outside winding thereof acts cumulatively with it. The current derived through the outside winding including the line relay of the first selector exerts a differential torque on the armatures of relay C, so relay C remains inert at this juncture. Upon the calling party sending digit "1" from sending device 20 the first selector will be caused to step up one level and rotate in one position, wipers 91, 92, 93 and 94 engaging and seizing bank contacts 95, 96, 97 and 98 respectively. Bank contacts 95, 96 and 97 lead over conductors 99, 100 and 101 respectively to the connector (designated Con.). The said connector may be assumed the type shown in U. S. Reissue No. 13,901, reissued Apr. 13, 1915, to Frank Newforth. A feature of the referred to connector is its function which causes the current supplied over the calling line to be reversed in direction incident to the called party responding, and this function lends itself to the purposes and objects of the present invention; that is, controls the registration of the meter device herein contemplated.
- Upon the calling party sending the last two digits of the called number (11) the connector wipers will be caused to step up one level and in one rotary position, the wipers 102, 103 and 104 engaging and seizing bank contacts 105, 106 and 107. The latter three contacts correspond in object and relation to bank contacts 108, 109 and 110 leading from the pre-selector on the calling line. The foregoing is assuming that the called line is arranged for two-way service, which latter, however, is not essential to the purposes of the present invention, though in practice nearly all lines of an exchange are arranged for two-way service.
- The called line seized is rung upon in the well known manner. Also, incident to the called party responding the current supplied to the calling party is reversed in direction; all as contemplated in the cited patent to Newforth.
- The current normally derived serially through the outside winding of shunted relay C from the front bridge (or as commonly termed, the line relay) of the connector is of such direction that it (like from the line relay of the selector) tends to neutralize the tractive influence of the energized inside winding; this after the connector is seized by the first selector and until the called party responds. Thus, the armature of relay C re-

mains inert under the said condition. However, upon the called party responding and incidentally causing the current projected through the calling telephone (the circuit path of which includes the outside shunted winding of relay C) to be reversed in direction, both windings of relay C will energize cumulatively and the armatures of said C will attract.

Resistance 85 is short circuited by armature 112 engaging its working contact 113. The obstruction involved in resistance 85 being thus removed from the circuit path including the inside winding of relay C the current strength derived through the inside winding of said C will be augmented to a value wherein it will sustain the armature of relay C attracted regardless of the direction of current flow in the outside winding thereof.

The outside winding of relay C is short-circuited by armature 114 engaging its working contact 115. This renders the outside winding of relay C inactive. The relay C is now held actuated and locked by virtue of the current in the inside winding thereof.

Bearing in mind the periodic functioning of the interrupter device, the first attraction of its member 51 after relay C actuates causes ground on bus-bar 41 to be applied to bank contact 42 and over common conductor 116, conductor 117, armature 118, working contact 119, conductor 120, make-before-break contacts 121 and 122 of slow-releasing relay D, armature 124 and resting contact 125 of relay E to the winding of relay D, causing it (relay D) to attract and disassociate its winding from conductor 120 before member 51 leaves contact 42 on its upward stroke. The winding of relay D will lock from grounded conductor 65 through armature 123 and its working contact 122, armature 124 and its resting contact 125, and so remains actuated until the expiration of the period of relay D after the circuit path to ground from conductor 65 becomes opened, or by relay E actuating and attracting armature 124 from resting contact 125.

Spring sets 35—36, 37—38, and 39—40 are normal (the hour being assumed as two a. m.); therefore there is no ground on bank contacts 45, 126, 127, 169 and 46. Conductive member 129 which is insulated from (but attached to) member 51 electrically joins the five bank contact pairs successively as the said member 51 is drawn upwardly by the solenoid action. As for example, bank contacts 44 and 45 are momentarily joined electrically as member 129 coincidently engages them. This joining of bank contacts 44 and 45 occurs following the grounding of bank contact 42.

The first and only grounded bank contact to be encountered by member 129 is bank contact 128. This ground will be communicated through member 129 to bank contact 130 and

to common conductor 131, conductor 132, armature 133, working contact 134, armature 135, resting contact 136 to the winding of magnet G of the total meter device, (the total meter device operated thereby being designated "Total M."), causing it to actuate one time.

It may be stated here that the total meter device is a counting device consisting of a plurality (usually four or more) drums upon which are equally and uniformly spaced digits "1" to "0" inclusive. The said drums represent the units, tens, hundreds, etc., numerical orders. Each succeeding higher numerical order drum turns one-tenth of a revolution for each complete revolution of the immediately preceding numerical order drum. So a line observation across the drums at the initial point of the units drum will indicate the total number of unit steps the first or units drum has advanced from "1". Indicating drums of this kind are not new as used on counting devices, cyclometers, consecutive number printers, etc. Also, such counting devices have been used, operated by an electromagnet in metering traffic in telephone exchanges and on individual lines of such exchanges, the electro-magnet stepping or advancing the units drum one-tenth of a revolution incident to each actuation or operative energization of the said electro-magnet. Further, such meter-devices (usually termed "meters" or "call counters" in the parlance of the art) have been used, arranged to be controlled by a connector incident to a called party responding, the meter electromagnet functioning one time and thus advancing the units drum one digit-position incident thereto. Such use as the latter is referred to in the cited patent to Newforth.

However, meters heretofore known, so far as I am aware, have not contemplated variable registering. That is to say, the recording or integrating of a different value under different conditions or at different times of day, when a registerable call is made. As hereinbefore set forth, the present invention thus contemplates variable registration, and not simply and only a counting of the completed calls to telephone lines of the general subscribers.

The present invention does also contemplate a supplemental meter device similar to the total meter device (designated "No. calls M"), which simply integrates the number of completed calls to general subscribers; each said call at equal meter value. The latter meter device is similar in general mechanical details to the total meter referred to. Thus, the meter or register contemplated in the present invention comprehends not only a means for recording the total number of calls completed to general subscribers, but also comprehends an integration of the chargeable values of each said calls com-

pleted, taking into account the time of day the call transpires, and if desired the destination of the call also.

Returning to the interrupter, after all the bank contact pairs have been engaged by member 129 member 51 applies ground received from grounded bus-bar 41 to contact 43 and over common conductor 137, conductor 138, working contact 139, armature 140, conductor 141, resting contact 142, make-before-break spring 143 to winding of relay E. Said E will actuate and lock through armature 144 to grounded conductor 65 before contact 43 is disengaged by member 51. Armature 135 attracting disengages contact 136, disassociating the winding of magnet G. This disassociation will continue as long as conductor 65 remains grounded.

Relay E upon actuating deenergizes relay D by attracting armature 124 from contact 125. However, an interval exists, due to the slow-releasing characteristic of relay D, wherein a closed circuit exists from the winding of the number of calls meter device magnet H, working contact 145, armature 146, working contact 147 to grounded armature 148, causing the said H to actuate and advance the cooperating units drum one digit space. This registers a call of unit value regardless of time of day or the destination of the call.

The connector referred to has the stated characteristic of reversing the current supplied to the calling party incident to the response of the called party and this causes the meter to function as set forth. However, in instances, it is desirable that no switching charge be made. For example, in calls to "Long distance", "Information", "Complaint", etc., no charge should be made. It is contemplated that the connector reaching such departments be modified so the current direction is not reversed to the calling party upon the department responding. Again, the call to such department may route through the selector only as contemplated in general in the patent to C. L. Zahm, No. 941,839, of Nov. 30, 1909. In such event the current supplied the calling subscriber will continue to be of the initial direction. Under such conditions relay C (and dependent relay D) will not actuate and therefore the meter (comprised of the total meter device and the number-of-calls-meter device) will not function. The outside winding of series relay C being non-inductively shunted will offer no appreciable obstruction to telephonic currents, though included in the telephonic path.

Upon the service through the pre-selector terminating, as by the calling party hanging his receiver on the switchhook, ground will be removed from the so-called private conductor 76, as set forth in the cited patent to Newforth. Consequent to this, conductor 120

65 will become ungrounded and all relays described as locked directly or indirectly to it will deenergize and restore to normal and the pre-selector will be ready for the initiation of a new call; the first selector engaged also restoring.

Assuming the stated call transpires at nine p. m. in place of two a. m. as first assumed. Then the shaft will have been revolved so cam 10 27 will cause contact springs 35—36 to be engaged. The latter condition will cause ground on spring 36 to be applied to contacts 127 and 46 of the interrupter. Bearing in mind the interrupter is functioning continuously periodically, each time the member 51 is drawn up, ground will be applied in sequence to common conductor 131 from contacts 149 and 130, and to common conductor 150 from contact 47.

20 Relay F is so designed as marginal that if unobstructed ground is applied to its winding, armatures 151 and 152 will engage working contacts 153 and 154 respectively. However, if obstructed ground (as represented by 25 the value of the resistance 155, for example) is thus applied, armature 151 only will engage its said working contact.

Wiper 94 in engaging a bank contact as 98 of the first level is applied directly to ground 30 and upon engaging a bank contact as 156 of the second level is applied to ground through resistance 155. All bank contacts of the first level adapted to be engaged by wiper 94 are commonly connected to unobstructed ground, 35 and all bank contacts of the second level adapted to be engaged by wiper 94 are commonly connected to grounded resistance 155. All bank contacts of the third level may be assumed as ungrounded. Thus, ground 40 from wiper 94, (when it engages a bank contact of the first or second levels) applies this ground over conductor 157, bank contact 158, wiper 159, conductor 160, armature 161, resting contact 162 to winding of relay F, causing 45 said F to actuate as set forth consistent with its marginal characteristic. It is clear from the foregoing that if the first selector wiper 94 engages a bank contact 163 of the third level in reaching some other similarly connected connector in access to a different line group or a line group in a different exchange office, relay F cannot function, and therefore no special or extra "trunking" charge involved in an extra impulse or impulses applied to magnet G will be integrated by the 50 registry of the total meter device because thereof.

The function of causing relay D to actuate incident to bank contact 42 being engaged 55 upon the first upward stroke of member 51, after relay C actuates consequent upon a response from on the called line will be as before described.

It will be assumed still that the present exampled call is to the same telephone Q as

before. Then due to contacts 35—36 being in engagement and contact 46 having ground thereon, when member 129 attached to member 51 engages contacts 46—47 conductor 150 will become grounded. Relay F being fully attracted because of wiper 94 being in engagement with contact 98 an extra impulse will be imparted to the total meter device by way of working contact 153, armature 151, conductor 165 to conductor 132, following the two impulses described as applied over conductor 131 and conductor 132. The units drum of the total meter device will thus be advanced three unit steps, representing the toll charge value of the assumed call at the stated hour. In the latter assumed instance a "trunking" charge of one point was made at the assumed time period because the line reached from the first selector passed over one of a group of trunks on the 1st level, to perhaps a remote office or in reaching a line to which an extra toll is charged. Relays D, E, and magnet H will function as before.

Had a trunk from the second level of the selector been selected in reaching the connector and telephone Q in the last exampled instance in lieu of the first level, the same functioning of total meter G would have taken place as described, for in either instance armature 151 would be in engagement with working contact 153.

Assuming the stated call transpires at eleven a. m. in place of two a. m. Then, shaft 30 will have revolved so cams 27, 28 and 29 will cause contact spring sets 35—36, 37—38 and 39—40 to be respectively engaged. The said contact condition will cause ground on spring 36 to be applied to contacts 127 and 46 as before; ground on spring 38 to contacts 126 and 169; and ground on spring 40 to contact 45. Thus, all lower contacts of each pair (45, 126, 127, 128, 169, and 46) are grounded.

When member 51 is raised the first time after relay C actuates relay D will actuate upon contact 42 being encountered by member 51 as before set forth. Then conductor 131 will be grounded four times successively while member 129 successively engages contact sets 45—44, 126—165, 127—149 and 128—130, followed by it engaging contact sets 169—166 and 46—47.

Wiper 94 of the first selector being in engagement with bank contact 98 armatures 151 and 152 will engage working contacts 153 and 154 respectively, and therefore the ground applied to common conductor 167 and conductor 168 from contact 166 and ground applied to conductor 150 and conductor 164 from contact 47 will be applied to conductor 132, making six ground impulses applied to conductor 132 incident to the stroke; relays D, E, and F functioning as before. In the present instance, two points of extra registry will be recorded by the total meter as a trunking charge. Of course, if the first selector

reached the connector and telephone Q from the third bank level in lieu of the first or second levels as before assumed, no trunking charge would be added because relay F will be normal due the wiper 94 failing to receive ground from an engaging bank contact.

The drawing hereto attached refers to a system including a pre-selector, a selector and a connector. This is by way of example only, for it is possible to annex or introduce additional selectors, or to omit the selector. In the latter case the conductors leading to wipers 91, 92 and 94 would be applied to wipers 102, 103 and 104 respectively in lieu thereof. In fact the contacts cooperating with wiper 94 may be on the connector, used to vary the charge between certain levels. In comprehensive exchanges there would, of course, be a plurality of successive selector elements involved in trunk links, the present invention being particularly adapted to such applications as referred to with relation to the trunking of calls. Further, the present invention is applicable to systems wherein operators control the interconnection of calling and called lines as distinct from systems wherein the calling party controls the interconnecting agency remotely through the agency of a calling device as 20 described.

30 The term "pre-selector" as used in the appended claims refers to a line switch for extending a calling line to an idle selector as shown, or it may be any adaptation which causes an idle selector to be extended to a calling line; termed a "line finder". Of course, the pre-selector may be dispensed with and equivalent meter circuits associated with the calling line and its associated terminal switch (in long distance service, for example), without departing from the scope of the present invention.

It is clear the wiper 159 may be omitted if a special charge is not to be made on certain trunked calls; also relay F therefore. Further, the cams on shaft 30 may be varied indefinitely as to their characteristics and number. Further, the number of contact sets on the interrupter may be increased or diminished and the registering values, representing toll charges may be widely altered. These modifications cited are by way of example only. Other modifications may be made as an amplification, or employed in part only without departing from the scope of the present invention.

Having thus described my invention what I claim as new and desire to secure by United States Letters Patent is:

1. In a telephone call meter mechanism 60 automatic means for recording variable toll charge values on like calls, regardless of the duration of the call.

2. In a telephone call meter mechanism automatic means for integrating variable

charge values on successive like calls regardless of the duration of the call. 65

3. In a telephone call meter mechanism a means to integrate variable charge values on successive like calls, the charge values depending upon the time of day each call transpires, regardless of the duration of the call. 70

4. In a telephone call meter mechanism, a means for integrating variable charge values on successive calls, the charge value depending upon the destination of the call, regardless of the duration of the call. 75

5. In a telephone call meter, a means for integrating variable charge values on successive calls, the charge values of each call depending upon the destination of the call and also upon the time of day the call transpires regardless of the duration of the call. 80

6. In a telephone system a calling and a called line, a pre-selector terminating the calling line having access to selectors and a connector forming a temporary connection train between the calling and the called lines, an impulse register specific to the calling line for integrating the number of impulses applied to it, an impulse sending means common to a plurality of like said coincident connections, and means responsive to an answer from the called line for applying the impulse sending means operative to the impulse register and for then disconnecting it for the duration of the call. 85 90

7. In a telephone system a calling and a called line, a pre-selector terminating the calling line having access to selectors and a connector forming a temporary connection train between the calling and the called lines, an impulse register specific to the calling line for integrating the number of impulses applied to it, an impulse sending means common to a plurality of like said coincident connections, means responsive to an answer from the called line for operatively applying the impulse sending means to the impulse register, and means for disassociating the impulse sending means for the duration of the call after a series of impulses has been operatively applied to the impulse register. 100 105 110

8. In a telephone system, a calling and a called line, a pre-selector terminating the calling line having access to selectors and a connector forming a temporary connection train between the calling and the called lines, an impulse register specific to the calling line for integrating the number of impulses applied to it, an impulse sending means common to a plurality of like said coincident connections for projecting series of impulses periodically, means associated with the pre-selector operative upon a response from the called line for operatively applying the impulse sending means to the impulse register, means for varying the number of impulses of 115 120 125

a respective said impulse series which may be operatively applied to the register, and means for preventing more than one series of impulses being applied regardless of the duration of a call.

9. In a telephone system, a calling and a called line, a pre-selector terminating the calling line having access to selectors and a connector forming a temporary train between the calling and the called line, an impulse register specific to the calling line for integrating the number of impulses applied to it, an impulse sending mechanism for projecting series of impulses periodically, auxiliary mechanism including a chronometer-controlled contact closing device for governing the number of impulses in a said series, means associated with the pre-selector operative upon a response from the called line for operatively applying the impulse sending means to the impulse register and for controlling the number of impulses of a respective said series which may be operatively applied to the register and means for preventing more than one series of impulses being applied regardless of the duration of a call.

10. In a telephone system, a calling line and called lines of two classes, a pre-selector terminating the calling line having access to switches forming a temporary train between the calling line and a called line and including the pre-selector, an impulse register specific to the calling line for integrating the number of impulses applied to it, an impulse sending mechanism for projecting series of impulses periodically, an auxiliary means for governing the number of impulses in a said series, mechanism associated with the pre-selector operative upon a response from a called line of one class only for operatively applying one series of impulses to the impulse register regardless of the duration of the call and for controlling the number of impulses of a respective said series which may be operatively applied to the register.

11. In a telephone system a calling and a called line, a pre-selector terminating the calling line having access to switches forming a temporary train between the calling line and the called line, an impulse register specific to the calling line for integrating the number of impulses applied to it, an impulse sending means for projecting series of impulses periodically, means associated with the pre-selector responsive to an answer from the called line for operatively applying the impulse sending means to the impulse register, one series of impulses operatively applied to said impulse register constituting the toll charge value of a completed call to the said called line regardless of the duration of the call, and means for controlling the number of impulses of a respective said series which may be operatively applied to the register.

12. In a telephone system a calling line and

a called toll line, other toll lines, a pre-selector terminating the calling line having access to switches forming a temporary train between the calling and the said called line or any other said toll line called, a first impulse register specific to the calling line for integrating the number of impulses applied to it, a second impulse register for integrating the number of calls completed to the said called line and also to any other called toll line, an impulse sending means for projecting series of impulses periodically, means associated with the pre-selector operative upon a response from a called line for operatively applying the impulse sending means to the said first impulse register, one series of impulses operatively applied to said impulse register constituting the toll charge value of a completed call under the calling condition, other means for controlling the number of impulses of a respective said series which may be operatively applied to the register regardless of the duration of the call, and further means for causing the said second impulse register to integrate an additional call of unit value consequent to a response from a called said line.

13. In a telephone system a calling line and a called toll line, other toll lines, a pre-selector terminating the calling line having access to switches forming a temporary train between the calling line and the said called line or any called toll line, an impulse register specific to the calling line for integrating toll charge values corresponding to the line called, an impulse sending means for projecting series of impulses, auxiliary means differently operative corresponding to a time schedule for governing the number of impulses in said series, and means operative upon a response from a called line for operatively applying the impulse sending means to the impulse register, one series of impulses operatively applied to said impulse register constituting the toll charge value of a completed call to a called one of said lines regardless of the duration of the call.

14. In a telephone system a calling line and a called toll line, other toll lines, a pre-selector terminating the calling line having access to switches forming a temporary train between the calling and the said called line or any called toll line, a first impulse register specific to the calling line for integrating toll charge values corresponding to the line called, an impulse sending means for projecting series of impulses, auxiliary means differently operative corresponding to a time schedule for governing the number of impulses in said series, means associated with the pre-selector operative upon a response on a called said line for operatively applying the impulse sending means to the first impulse register, one series of impulses operatively applied to said impulse register con-

- stituting the toll charge value of a completed call to a called one of said lines regardless of the duration of the call, a second impulse register for integrating the number of calls completed to the said called line or to any other said toll line called, and means for causing said second impulse register to integrate an additional call of unit value consequent to a response on a called said line.
15. In a telephone system, telephone lines, a pre-selector terminating a calling line having access to switches adapted to be inter-linked forming a temporary train between the calling and a called line, a first impulse register specific to the calling line for integrating toll charge values corresponding to the line called, an impulse sending means for projecting series of impulses, auxiliary means differently operative corresponding to a time schedule for governing the number of impulses in said series, means operative upon a response on a called said line for operatively applying the impulse sending means to the first impulse register, each series of impulses operatively applied to said impulse register constituting the toll charge value of a completed call to the called line regardless of the duration of the call, a second impulse register for integrating the number of calls completed to the said called line, and means for causing said second impulse register to integrate an additional call of unit value consequent to a response on the called said line.
16. In a telephone system, telephone lines, switches forming a temporary train between a calling and a called line, an impulse register specific to the calling line for integrating toll charge values corresponding to the line called, an impulse sending means for projecting series of impulses, auxiliary means differently operative corresponding to a time schedule for governing the number of impulses in said series, means responsive to an answer from the called line for operatively applying the impulse sending means to the register, one series of impulses operatively applied to said impulse register constituting the toll charge value of a completed call to the called line, and means for rendering the register non-responsive to the impulse sending means after the register has integrated a series of impulses.
17. In a telephone system, telephone lines, switches forming a temporary train between a calling and a called line, a first impulse register specific to the calling line for integrating toll charge values corresponding to the line called, an impulse sending means for projecting series of impulses, auxiliary means differently operative corresponding to a time schedule for governing the number of impulses in said series, means operative upon a response from the called line for operatively applying the impulse sending means operative to the register, one series of impulses operatively applied to said impulse register constituting the toll charge value of a completed call to the called line, a second impulse register for integrating the number of calls completed to the said called line, means for causing said second impulse register to integrate an additional call of unit value consequent to a response on the called line, and means for rendering the impulse registers non-responsive after the registers have integrated.
18. In a telephone system, telephone lines, switches forming a temporary connection train between a calling and a called line, an impulse register specific to the calling line for integrating toll charge values corresponding to the line called but irrespective of the duration of the call, an impulse sending means common to a plurality of like said connections for projecting a series of impulses for operating the register, a circuit closing contact and means including an auxiliary wiper of one of the switches cooperating with the circuit-closing contact for altering the number of operative impulses in a series effective to only the specific impulse register of the first said connection.
19. In a telephone system, telephone lines, switches adapted to be interlinked under control of means on a calling line forming a temporary connection train between the calling and a called line, an impulse register specific to the calling line for integrating toll charge values corresponding to the line called operative upon response on the called line but irrespective of the duration of the call, an impulse sending means common to a plurality of like said connections for projecting impulses for operating the register, a circuit closing contact and means including an auxiliary wiper of one of the switches cooperating with the circuit-closing contact for altering the number of operative impulses in a series effective to only the specific impulse register of the first said connection.
20. In a telephone system, connected telephone lines, a call register, a device for operatively projecting series of impulses to said register, means controlled by a manual operation on one of the lines following the connecting of the lines for applying a series of impulses to said register, the number of impulses in the series being automatically determined by the time of day the said manual operation occurs, and means for disconnecting the said means at the termination of the series before the lines are disconnected regardless of the duration of the connection.
21. In a telephone system, connected telephone lines, a call register, a device for operatively projecting impulses to said register in a series, means controlled by a manual operation on one of the lines following the connecting of the lines for applying the impulses to said register, the number of im-

pulses in the series being automatically determined by the time of day the said manual operation occurs, and means for preventing further application of impulses to said register after the termination of the series regardless of the duration of the connection.

22. In a telephone system, a calling line, a trunk line, a toll assessing device for the calling line, a called line, mechanism associated with the toll assessing device for varying the amount assessed for a connection extended from the calling line to the trunk line, mechanism associated with the toll assessing device for varying the amount assessed for a connection extended over the trunk line portion independent of the amount assessed for the portion of the connection from the calling line to the trunk line, means for connecting the calling line with the called line over the trunk line as a link of the connection, and means whereby the amount assessed for a completed connection will equal the sum of the assessments on the portion of the connection from the calling line to the trunk line and the portion of the connection over the trunk line.

23. In a telephone system, a calling line, a trunk line, a toll assessing device for the calling line, a called line, mechanism associated with the toll assessing device for varying the amount assessed for a connection extended from the calling line to the trunk line, mechanism associated with the toll assessing device for varying the amount assessed for a connection extended over the trunk line portion independent of the amount assessed for the portion of the connection from the calling line to the trunk line, means for connecting the calling line with the called line over the trunk line as a link of the connection, means whereby the amount assessed for a connection will equal the sum of the assessments on the portion of the call from the calling line to the trunk line and the portion of the connection over the trunk line, and means for recording the total assessment.

24. In a telephone system, a calling line, a trunk line, a toll assessing device associated with the calling line, a called line, a chronometer controlled mechanism associated with the toll assessing device for varying the amount assessed for a connection extended from the calling line to the trunk line, a chronometer controlled mechanism associated with the toll assessing device for varying the amount assessed for a connection extended over the trunk line portion independent of the amount assessed for the portion of the connection from the calling line to the trunk line according to the time of day, means for connecting the calling line with the called line over the trunk line as a link of the connection, and means whereby the amount assessed for a connection will equal the sum of the assessments on the portion of

the connection from the calling line to the trunk line and the portion of the connection over the trunk line.

25. In a telephone system, a calling line, a trunk line, a toll assessing device for the calling line, a called line, a linked connection between the calling line and the called line involving two said line sections, toll assessing mechanism independently operated from each section of the connection controlled over the called line responsive to a manual operation, and means whereby the amount assessed for a connection will equal the sum of the assessments for each said section, each said assessment independently depending upon the time of day at which the said manual operation occurs.

26. In a telephone system, a calling line, a trunk line, a toll assessing device for the calling line, a called line, a linked connection between the calling line and the called line involving two said line sections, toll assessing mechanism independently operated from each section of the connection controlled over the called line responsive to a manual operation, means whereby the amount assessed for a connection will equal the sum of the assessments for each said section, means whereby the amount assessed for each section will depend upon the time of day at which the said manual operation occurs, and means for recording the total assessment on the toll assessing device.

27. In a telephone system, a calling line, a trunk line, a toll assessing device for the calling line, a called line, a linked connection between the calling line and the called line involving two said line sections, toll assessing chronometer operated responsive mechanism independently controlled to a connection specific to each section of the connection controlled over the called line responsive to a manual operation, and means whereby the amount assessed for a connection will equal the sum of the assessments for each said section and depend upon the time of day the said manual operation occurs.

28. In a telephone system, a calling line, a plurality of trunk lines, a toll assessing device for the calling line, a plurality of called lines, means for linking successive connections from the calling line over the respective trunk lines to different ones of the called lines, variable toll assessing mechanism controlled from the respective trunk lines whereby the assessed toll thereover will depend upon a specific condition thereof made variable with the time of day, toll assessing mechanism associated with the calling line independent of a linked trunk line, and means whereby the amount assessed for a call will equal the sum of the assessment of the said calling line mechanism and the assessment for the linked trunk line.

29. In a telephone system, a calling line,

- a plurality of trunk links, a toll assessing device for the calling line, a called line, mechanism for recording independent toll charges for the respective said trunk links, means to vary the latter said toll charges in accordance with the time of day, and means to operate the toll assessing device whereby it will record the sum of the toll charges of the respective links.
- 10 30. In a telephone system, a calling line, a plurality of trunk links, a toll assessing device for the calling line, a called line, mechanism for operating the assessing device to record independent toll charges for the respective said trunk links, means to vary the latter said toll charges according to the time of day, and means controlled over the calling line to operate the toll assessing device whereby it will record the sum of the toll charges of the respective links.
- 15 31. In a telephone system, a calling line, a plurality of trunk links, a toll assessing device for the calling line, a called line, mechanism for operating the assessing device to record independent toll charges for the respective said trunk links, the said mechanism being disabled dependent upon a response on the called line for enabling it to operate from normal, and means effectively controlled consequent upon the response on the called line to record the sum of the toll charges of the respective links.
- 20 32. In a telephone system, a calling line, a plurality of trunk links, a called line, a toll assessing device associated with the calling line, mechanism for recording independent toll charges for the respective said trunk links in a connection from the calling to the called line, the charges appertaining to each said link being subject to independent variation depending upon the time of day the toll is assessed, and means for causing the toll assessing device to register the total charge involved in the respective said links of a call.
- 25 33. In a telephone system, a plurality of line sections, a polarized relay associated with a first one of the sections, means for interlinking the said sections in tandem, a source of current applied from a second one of the sections to the said first section and to the winding of said relay but operatively non-effective thereto, means for changing the direction of current flow whereby the current will thereafter be operatively effective to the relay, means to restore the direction of current flow to that primarily existing, and means to prevent the relay from being operatively affected because of the said restoration of the direction of current flow.
- 30 34. In a telephone system, a plurality of line sections, an electro-polarized relay, a polarizing winding for said relay, an energizing source for said polarizing winding, a resistor normally included in a path with said polarizing winding, a second winding for said relay associated with a first one of the said sections, means for interlinking the said sections in tandem, a second source of current applied from a second one of the said sections to energize the said second winding opposingly to the said polarizing winding, means for reversing the direction of current projected from the said second source to the said second one of said sections whereby the two said windings will energize the relay cumulatively to operate it, means to short-circuit the resistor consequent to the operation of the relay whereby the electro-polarizing winding will become energized to predominate the said second winding regardless of the direction of current therein, and means to maintain the resistor short-circuited consequent to the reversing of the direction of current regardless of any subsequent change in the direction of the current.
- 35 35. In a telephone system, a plurality of line sections, an electro-polarized relay, a polarizing winding for said relay, an energizing source for said polarizing winding, a resistor normally included in a path with said polarizing winding, a second winding for said relay in a series path with a portion of a first one of the said sections, means for interlinking the said sections in tandem, a source of current applied from a successive second one of the said sections to energize the said second winding opposingly to the said polarizing winding, means for reversing the direction of current projected from the said second source whereby the said second winding will energize cumulatively with the said first winding to operate the relay, means to short-circuit the resistor consequent to the operation of the relay whereby the electro-polarizing winding will become energized to predominate the said second winding regardless of the direction of current therein, and means to maintain the resistor short-circuited consequent to the reversing of the direction of current regardless of any subsequent change in the direction of current in the said second winding.
- 40 36. A relay having a first electro-polarizing winding on its core, an auxiliary resistor included with said winding, a source of energizing current for said winding, a second independently energized winding electro-magnetically related to the core of the relay in common with said first winding, the relay being operatively affected when the two said windings are energized cumulatively, but not operatively affected when the windings are energizing opposingly, means for reversing the direction of current in the said second winding, means for altering the relation of the said resistor whereby the current in the said first winding then predominates the influence of the said second winding regardless of the direction of current traversing the said second winding, and means for caus-

ing the said first winding to predominate the said second winding regardless of the direction of current traversing the said second winding whereby the relay will become 5 locked actuated consequently to the two said windings energizing cumulatively.

37. A relay, a polarizing winding and an operative winding for said relay, a source of current for the operative winding which 10 may be applied in opposite directions whereby the relay will actuate if the current in the said operative winding is in a predetermined direction and remain normal if it is not, and means to predominate the said polarizing 15 winding upon the actuation of the relay so that the relay will thereafter remain actuated regardless of the direction of current in the operative winding.

38. In a telephone system, a calling line, a 20 trunk line, a toll assessing device for the calling line, a called line, mechanism associated with the toll assessing device for varying the amount assessed for a connection extended from the calling line to the trunk line depending 25 upon the time of day, mechanism associated with the toll assessing device for varying the amount assessed for a connection extended over the trunk line portion independent of the amount assessed for the portion of 30 the connection from the calling line to the trunk line, means for connecting the calling line with the called line over the trunk line as a link of the connection, and means whereby the amount assessed for a completed connection 35 will equal the sum of the assessments on the portion of the connection from the calling line to the trunk line and the portion of the connection over the trunk line.

39. In a telephone system, a plurality of 40 pairs of connected calling and called telephone lines, a call toll register for the calling line of each pair, a device common to all the call registers for projecting a train of impulses operatively effective to the respective 45 said registers coincidently, and means independently controlled over the respective called lines of the pairs for causing only the register on its respective paired line to be effectively operated.

40. In a telephone system, a plurality of pairs of connected calling and called telephone lines, a call toll register for the calling line of each pair, a device common to all the call registers for projecting a train of impulses operatively effective to the respective 55 said registers coincidently, means independently controlled over the respective called lines of the pairs for causing only the register on its respective paired line to be effectively operated, and means operative dependent upon a trunk line being interposed between the calling and a called line pair for causing a different train of impulses to be applied by the said device to the register of 60 its connected calling line than to registers of 65

calling lines of said paired connections wherein no trunk line is interposed.

41. In a telephone system, a plurality of calling lines, a call toll meter companion to each calling line respectively, called lines to which the respective calling lines are temporarily connected, a mechanism for commonly operating the said meters to register different tolls in accordance with what called line is connected to its companion calling line, and means controlled over the called line of a connection to cause the said mechanism to operate the corresponding calling line toll meter independently of the operation of other meters coincidently operated thereby. 75

42. In a telephone system, a plurality of calling lines, a call toll meter companion to each calling line respectively, called lines to which the respective calling lines are temporarily connected, a mechanism for commonly operating the said meters to register different tolls in accordance with what called line is connected to its companion calling line and the time of day the registration occurs, and means controlled over the called line of a connection to cause the said mechanism to operate the corresponding calling line toll meter independently of the operation of other meters coincidently operated thereby. 80

43. In a telephone system, a plurality of calling lines, a toll meter companion to each calling line respectively, called lines to which the respective calling lines are temporarily connected, a periodically operating mechanism common to the calling line meters for sending an impulse train at each operation, the train varying with the time of day, means controlled over a connected called line for causing the said mechanism to apply its next succeeding train of impulses to the 100 meter of the respective companion calling line, means automatically controlled by the said mechanism for preventing more than one train to be applied effective to a specific meter during a sustained connection of its companion calling line, and means whereby the said mechanism may commonly serve a plurality of coincident said connections without affecting its normal operation with respect to any 110 said connection. 115

44. In a telephone system, a plurality of calling lines, a toll meter companion to each calling line respectively, called lines to which the respective calling lines are temporarily connected, a periodically operating mechanism common to the calling line meters for sending an impulse train at each operation, means controlled over a connected called line for causing the said mechanism to apply its next succeeding train of impulses to the 120 meter of the respective companion calling line, means automatically controlled by the said mechanism for preventing more than one train to be applied effective to a specific 125 meter during a sustained connection of its 130

companion calling line, and means whereby the said mechanism may commonly serve a plurality of coincident said connections without affecting its normal operation with respect to any said connection.

45. In a telephone system, a plurality of calling lines, a toll meter companion to each calling line respectively, called lines to which the respective calling lines are temporarily connected, a periodically operating mechanism common to the calling line meters for sending an impulse train at each operation, the train varying with the time of day, means controlled over a connected called line for causing the said mechanism to apply the next succeeding train of impulses to the meter of the respective companion calling line, and means automatically controlled by the said mechanism for preventing more than one train to be applied effective to a specific meter during a sustained connection of its companion calling line.

46. In a telephone system, a plurality of calling lines, a toll meter companion to each calling line respectively, called lines to which the respective calling lines are temporarily connected, a periodically operating mechanism common to the calling line meters for sending an impulse train at each operation, means controlled over a connected called line for causing the said mechanism to apply its next succeeding train of impulses to the meter of the respective companion calling line, and means automatically controlled by the said mechanism for preventing more than one train to be applied effective to a specific meter during a sustained connection of its companion calling line.

47. In a telephone system, a calling line, a toll meter companion to the calling line, a called line; the calling and called line being temporarily connected, a periodically operating mechanism for sending an impulse train at each operation, means controlled over the called line for causing the said mechanism to apply its next succeeding train of impulses to the toll meter, and means automatically controlled by the said mechanism for preventing more than one train to be applied effective to the toll meter during a sustained connection.

48. In a telephone system, a calling line, a toll meter companion to the calling line, a called line, the calling and called line being temporarily connected, a periodically operating mechanism for sending an impulse train at each operation, the train varying with the time of day, means controlled over the called line for causing the said mechanism to apply its next succeeding train of impulses to the toll meter, and means automatically controlled by the said mechanism for preventing more than one train to be applied effective to the toll meter during a sustained connection.

49. In a telephone system, a calling line, a toll meter companion to the calling line, a called line, the calling and called line being temporarily connected a periodically operating mechanism for sending an impulse train at each operation, the train varying with the time of day, means controlled over the called line for causing the said mechanism to apply its next succeeding train of impulses to the toll meter, means for preventing less than a complete train being applied effective to the meter, and means automatically controlled by the said mechanism for preventing more than one train to be applied effective to the toll meter during a sustained connection.

50. In a telephone system, a calling line, a toll meter companion to the calling line, a called line, the calling and called line being temporarily connected, a periodically operating mechanism for sending an impulse train at each operation, means controlled over the called line for causing the said mechanism to apply its next succeeding train of impulses to the toll meter, means for preventing less than a complete train being applied effective to the toll meter, and means automatically controlled by the said mechanism for preventing more than one train to be applied effective to the toll meter during a sustained connection.

51. In a telephone system, a calling line, a first and a second toll meter companion to the calling line, a called line, the calling and called line being temporarily connected, a periodically operating mechanism for sending an impulse train at each operation, the train varying with the time of day, means controlled over the called line for causing the said mechanism to apply its next succeeding train of impulses to the first toll meter, means for preventing less than a complete train being applied effective to the first toll meter, means automatically controlled by the said mechanism for preventing more than one train to be applied effective to the toll meter during a sustained connection, and means for applying one impulse to the second toll meter incident to applying the train effective to the first meter.

52. In a telephone system, a calling line, a first and a second toll meter companion to the calling line, a called line, the calling and called line being temporarily connected, a periodically operating mechanism for sending an impulse train at each operation, means controlled over the called line for causing the said mechanism to apply its next succeeding train of impulses to the first toll meter, means for preventing less than a complete train being applied effective to the first toll meter, means automatically controlled by the said mechanism for preventing more than one train to be applied effective to the toll meter during a sustained connection, and means for applying one impulse to the sec-

ond toll meter incident to applying the train effective to the first meter.

53. In a telephone system, a calling line, a first and a second toll meter companion to the calling line, a called line, the calling and called line being temporarily connected, a periodically operating mechanism for sending an impulse train at each operation, means controlled over the called line for causing the said mechanism to apply its next succeeding train of impulses to the first toll meter, means for preventing less than a complete train being applied effective to the first toll meter, and means for applying only one impulse to the second toll meter during a sustained connection between the calling and called line, the said one impulse being applied incident to applying a train effective to the first meter.
- 10 54. In a telephone system, a calling line, a toll meter companion to the calling line, a called line, the calling and called line being temporarily connected, a periodically operating mechanism for sending an impulse train at each operation, means controlled over the called line for causing the said mechanism to apply its next succeeding train of impulses to the toll meter, and means for preventing less than a complete train being applied effective to the toll meter.

55. In a telephone system, a calling line, a toll meter companion to the calling line, a called line, the calling and called line being temporarily connected, another calling and called line like connection, a periodically operating mechanism common to the said connections for sending an impulse train at each operation, means controlled over a called said line for causing the said mechanism to apply its next succeeding train of impulses to the toll meter of the companion calling line of the last said called line, and means for preventing less than a complete train being applied effective to the toll meter.

- 45 56. In a telephone system, switch mechanism for extending connections between calling and called lines of the system, a charging device for assessing toll charges for respective said connections, and means whereby a specific predetermined charge will be made by the charging device on the respective connections which specific charge will be variable only dependent upon which specific said lines are connected and upon the time of day the connection is made.

- 60 57. In a telephone system, switch mechanism for extending connections between calling and called lines of the system, a charging device for assessing and recording toll charges for respective said connections, and means whereby a specific predetermined charge will be made by the charging device on the respective connections which specific charge will be variable only dependent upon which specific said lines are connected and

upon the time of day the connection is made.

58. In a telephone system, switch mechanism for extending and thereafter destroying talking connections between calling and called lines of the system, a charging device for assessing toll charges for respective said talking connections, and means for varying the charge for a single talking connection dependent upon the time of day the talking connection is effected irrespective of the time of day the connection is destroyed.

59. In a telephone system, switch mechanism for extending and thereafter destroying talking connections between calling and called lines of the system, means for automatically assessing a toll charge for the connection regardless of what time of day the connection occurs, and means for assessing an additional toll charge only provided the connection occurs at a predetermined specific time of day regardless of when it is destroyed.

60. In a telephone system, switch mechanism for extending and thereafter destroying talking connections between calling and called lines of the system, means for automatically assessing a toll charge for the connection regardless of its duration, and means for assessing an additional charge for the connection which latter charge will vary in amount dependent upon the time of day the connection occurs.

61. In a telephone system, switch mechanism for extending and thereafter destroying talking connections between calling and called lines of the system, means for automatically assessing a toll charge for the connection regardless of its duration, and means for assessing an additional charge for the connection which latter charge will vary in amount dependent upon the time of day the connection occurs regardless of the duration of the connection.

62. In a telephone system, telephone lines, switches forming a temporary connection train between a calling line and a called line, an impulse register specific to the calling line for integrating toll charge values corresponding to the line called but irrespective of the duration of the call, an impulse sending means common to a plurality of like said connections for projecting a series of impulses for operating the respective registers coincidentally, and means for altering the number of operative impulses in a said series effective to only the specific impulse register of the first said connection.

63. In a telephone system, telephone lines, switches forming a temporary connection train between a calling line and a called line, an impulse register specific to the calling line for integrating toll charge values corresponding to the line called but irrespective of the duration of the call, an impulse sending means common to a plurality of like said connections for projecting a series of impulses for operat-

ing the respective registers coincidently, and means whereby the impulse sending means will send impulses of different number effective to coincidently occurring connections

5 wherein the first and last impulse of the series of different number will be coincidently applied and wherein the time occupied in sending the series of different number of impulses to the registers will be equal and coincident.

10 64. In a telephone system, switch mechanism for extending connections between calling and called lines of the system, a charging device for assessing a toll charge for respective said connections, and means whereby the removal of the receiver of the telephone on the line called will cause a toll charge to be assessed by its corresponding charging device regardless of how soon the receiver is replaced but variable in amount with the time of day the receiver is removed.

15 65. In a telephone system, switch mechanism for extending connections between calling and called lines of the system, a charging device for assessing a toll charge for respective said connections, means controlled from the calling line for destroying the connection at will, means whereby the removal of the receiver of the telephone on the called line will cause the toll charge to be assessed regardless of how soon the receiver is replaced, and means for preventing the connection from being destroyed if the receiver of the telephone on the called line has been removed 30 until a toll charge has been assessed regardless of the fact it may be replaced before the assessment has been made.

20 66. In a telephone system, a calling line, a trunk line, a called line, switch mechanism for linking a connection from the calling line over the trunk line to the called line, a toll assessing device for the calling line, means for operating the assessing device for calls completed from the calling line to the called line wherein a specific assessment is made 45 for the use of the trunk line in the connection, and clock-controlled means for varying the said assessment in accordance with the time of day the call is completed irrespective of any other toll assessment made for the connection.

50 67. In a telephone system, a calling line, a trunk line, a called line, switch mechanism for linking a connection from the calling line over the trunk line to the called line, a toll assessing device for the calling line, and means operated responsive to the party on the called line removing his receiver in responding to the call to cause the assessing device to 55 operate to assess a charge for the connection, a charge depending upon the time of day the call transpires, and a charge for the trunk line.

68. In a telephone system, a calling line, a 65 trunk line, a called line, switch mechanism for

linking a connection from the calling line over the trunk line to the called line, a toll assessing device for the calling line, and means operated responsive to the party on the called line removing his receiver in responding to the call to first cause the assessing device to operate to assess a charge for the connection, to then operate to assess a charge depending upon the time of day the call transpires, and to then operate to assess a charge 75 for the trunk line.

69. In a telephone system, a calling line, a trunk line, a called line, switch mechanism for linking a connection from the calling line over the trunk line to the called line, a toll assessing device for the calling line, and means operated responsive to the called party removing his receiver from the switch-hook in responding to cause the assessing device to operate to assess a charge for the connection, a charge depending upon the time of day the call transpires, and a charge for the trunk line 80 wherein the total charge for the connection is the sum of said individual charges and variable with any one of them.

70. A relay having a first electro-polarizing winding on its core, a resistor included serially with said winding, a source of energizing current for said winding and series resistor, a second independently energized winding electro-magnetically related to the core of the relay commonly with said first winding, an armature of the relay, means for reversing the direction of current in said second winding, means for operating the armature to exclude the resistor from the energizing circuit of the polarizing winding responsive to said reversal, and means responsive to the operation of said armature to lock it in its actuated position regardless of the direction of current 105 traversing the said second winding.

71. A relay having a first electro-polarizing winding on its core, a resistor included serially with said winding, a source of energizing current for said winding and series resistor, a second independently energized winding electro-magnetically related to the core of the relay commonly with said first winding, an armature of the relay, means for reversing the direction of current in one of said windings, means for operating the armature for excluding the resistor from the energizing circuit of the polarizing winding responsive to said reversal, and means responsive to the operation of said armature to lock it in its actuated position regardless of the direction of current 110 traversing the said second winding.

72. A relay having a first electro-polarizing winding on its core, a resistor associated with said winding, a source of energizing current for said winding and associated resistor, a second independently energized winding electro-magnetically related to the core of the relay commonly with said first winding, an 115 120 125 130

armature of the relay, means for reversing the direction of current in one of said windings, means for operating the armature to augment the current strength in the energizing circuit of the polarizing winding responsive to said reversal, and means responsive to the operation of said armature to lock it in its actuated position regardless of the direction of current traversing the said 10 second winding.

73. A relay having a first electro-polarizing winding on its core, a resistor associated with said winding, a source of energizing current for said winding and associated resistor, 15 a second independently energized winding electro-magnetically related to the core of the relay commonly with said first winding, armatures of the relay, means for reversing the direction of current in one of said windings, means for operating the armatures and 20 to affect the relation of the resistor with respect to the polarizing winding responsive to said reversal and means responsive to the said affected relation of the resistor for locking the armatures in their actuated position 25 regardless of the direction of current traversing the said second winding.

74. In a telephone system, a plurality of calling lines, a toll meter companion to each 30 calling line respectively, called lines to which the respective calling lines are temporarily connected, a periodically operating mechanism common to the calling line meters for sending impulses in trains, means controlled 35 over a connected called line for causing the said mechanism to apply its next succeeding train of impulses to the meter of the respective companion calling line, means for preventing impulses of a train being applied to 40 the meter of a connection if said control is applied over the called line of the connection after the said mechanism has started effecting a train of series, means automatically controlled by the said mechanism for preventing

more than one train to be applied effective to 45 a specific meter during a sustained connection involving its companion calling line, and means whereby the said mechanism may commonly serve a plurality of coincident said connections without affecting its normal operation with respect to any single said connection.

75. In a mechanism for sending successive trains of impulses, automatic means controlled by a clock in accordance with the time 50 of day for varying the number of impulses in each said train.

76. In a mechanism for sending successive trains of impulses, a plurality of conductors, means for sending a train of impulses applied interchangeably over said conductors, and automatic means controlled by a clock in accordance with the time of day for varying the number of impulses in each said train.

77. In a mechanism for sending successive trains of electrical impulses, means whereby the first and last impulse of a train will be uniformly spaced regardless of the number of impulses in the train, and means controlled by a clock in accordance with the time of day 70 for varying the number of impulses in a said train.

78. In a mechanism for sending successive trains of electrical impulses to a conductor, means for sending successive trains of said impulses continuously, and means whereby the first and last impulse of a train will be uniformly spaced regardless of the number of impulses in the train, and means controlled by a clock in accordance with the time of day 75 for varying the number of impulses in said trains wherein consecutive trains of said impulses may consist of the same number of impulses for each train.

In witness whereof, I hereunto subscribe 85 my name this 21st day of Oct. A. D., 1920.

HERBERT M. FRIENDLY.
